INFLATED TOY FIGURE

Irvin J. Gershen, Springfield, N.J., assignor to Johnson & Johnson, a corporation of New Jersey

Filed Feb. 9, 1966, Ser. No. 981

Term of patent 14 years

(Cl. D34—15)

FIG. 1.

FIG. 2.

FIG. 1.

FIG. 1 is a perspective view of an inflated toy figure showing my design the side opposite FIG. 1 is plain and unornamented;

FIG. 2 is a front end view of the toy shown in FIG. 1 the opposite side being substantially the same.

I claim:

The ornamental design for an inflated toy figure, as shown and described.
